PROJECTILE TOY

Otto Schrickel, Mirror Pools, Mount Healthy,
Ohio

Application February 4, 1935, Serial No. 4,840

7 Claims. (Cl. 273—96)

The present invention relates to a projectile toy, of a type wherein a ring or short cylinder may be projected either vertically or at any upward inclination not less than 45 degrees, at 5 which inclinations the ring will return to the operator in descending, so that the operator may readily recover it in flight.

An object of the invention is to provide a device for the above purpose, which is simple to 10 operate and very inexpensive to manufacture.

Another object is to provide a toy of the projectile type which is not capable of inflicting injury upon bystanders or the operator, and which 15 may not be used in such manner as to be destructive of property; the device may be used indoors as well as outside of a building.

A further object of the invention is to provide a device of the character stated, which may be used in playing games, or which may have its 20 projected part or parts decorated or marked so as to present a pleasing color effect or illusion while in flight.

The foregoing and other objects are attained by the means described herein and disclosed in 25 the accompanying drawing, in which:

Fig. 1 is a perspective view of the device, shown in readiness for use, the line of flight of the ring 6 being indicated by broken lines.

Fig. 2 is an enlarged top plan view of the Fig. 30 1 device.

Fig. 3 is an enlarged perspective view of one part of the ring-projecting and recovering head of the device.

Fig. 4 is an enlarged fragmental perspective 35 view of the upper shaft end of the device.

Fig. 5 is a cross-sectional view taken on line 5—5 of Fig. 1.

The device of the invention comprises a shaft 7, preferably circular in cross section, which 40 shaft carries at its upper end 8 a ring-projecting and recovering head, indicated generally by the character 9. The head may be made spear shaped, or in the shape of a cone or pyramid, if desired, so that the lower edge 10 of ring 6 may 45 rest upon the outer edges or narrow faces 12 when the ring is in position thereon. At the lower end of the shaft 7 is anchored the lower end 13 of a coiled tension spring 14, the upper end of which spring is anchored at 15 upon a rotatable sleeve 16 which is slidable longitudinally of the shaft in opposition to the resistance of the spring. Preferably, though not necessarily, the lower end 50 of shaft 7 is provided with an enlargement 17 which provides a fixed handle whereby the shaft 55 may be rotated and retracted by the fingers of one hand while the fingers of the other hand hold the sleeve 16. The enlargement or handle 17 may be made tubular, and fitted to the shaft end in such manner as to maintain the diametrically 60 disposed spring end 13 securely within the slot 28.

With reference to the upper end 18 of shaft 7, it may be stated that the ring-projecting and recovering head 9 may be constructed in any suitable manner, and of any suitable material which, for the purpose of reducing expense, may be of heavy cardboard or like material. Although various modes of assembly and construction may be employed in shaping and fixedly mounting the head upon the upper end of the shaft, I have disclosed herein an acceptable construction and mounting means for the head. In accordance with the disclosures of Figs. 3 and 4, the upper end of shaft 7 is provided with a series of radial slots or cross-cuts 18, 19, 20 and 21, said slots or cuts being adapted to receive the 15 four wings or vanes 180, 190, 120 and 121 of the pair of head parts or constituents 22 and 23. As will be understood, the head part 22 is identical with the head part 23, and it comprises a triangular sheet of material bent along a score line 20 24 extending from an apex 25 perpendicularly to the opposite edge of base 26. The wings or vanes 180 and 190 are extended substantially at right angles to one another as is clearly illustrated in Fig. 2. The vanes or wings 180 and 190 are secured within the slots 18 and 19, 25 whereas the vanes 120 and 121 are similarly secured within the opposite slots or seats 20 and 21, this being clearly illustrated in Fig. 2. If desired, cement or glue or other fastening means 30 may be employed to maintain the head parts or constituents in fixed relationship with the upper end of the shaft.

The operation of the device is as follows:

The operator of the device, after placing one or 35 more rings such as 6 and 60 upon the spear head, holds the sleeve 16 with the fingers of the left hand, while the fingers of the right hand are applied to the handle end 17 for the purpose of slightly rotating the shaft 7 while at the same 40 time withdrawing the shaft downwardly through the sleeve. By releasing the hold on the handle end 17 and maintaining a hold on the sleeve 16, the shaft 7 will have imparted thereto a sudden upward and rotational movement which acts to 45 project the ring or rings into the air along a definite line of flight while the ring rotates about its imaginary center. The ring, being of light weight and of thin material, will travel upwardly along a substantially straight line of flight and 50 after reaching a predetermined height will descend along substantially the same line of flight so that the operator may readily recover the ring in flight by catching it upon the head 9. The device is then ready for a subsequent actuation. 55

The ring or rings to be projected may be constructed of paper, cardboard, celluloid or the like and may be suitably decorated or marked to present a pleasing color effect or illusion while in flight. To more definitely set forth the char- 60

acteristics of the rings, it may be stated that each ring is a short transverse section or length of a substantially true cylinder. To obtain the best results, the ring or rings are constructed of thin light-weight material. The ring may be projected either vertically or at any upward inclination, but to insure the return of the ring to the operator, the inclination should be not less than approximately 45 degrees.

It will readily be evident that the device of 10 this invention is simple to operate and very inexpensive to manufacture, and that it is not capable of inflicting injury to persons or destruction to property. The device may be used in playing games of skill, either indoors or outdoors, or it may be decorated or marked for securing pleasing color effects or illusions.

As stated above, the ring-projecting and recovering head may be of any suitable shape, or 20 constructed in any approved manner for fixation thereof to the upper end of the shaft 7. The lower end 13 of the spring 14 may be fixed directly to the lower end of shaft 7, without employing a fixed handle such as 17. It is to be understood that various other modifications and 25 changes in the structural details of the device may be made, within the scope of the appended claims without departing from the spirit of the invention.

What is claimed is:

30 1. A returning-projectile toy comprising the combination of a thin-walled light-weight tube of a height greatly exceeding the thickness of its wall, and means including a shaft with a tube support fixed thereto, for imparting to the 35 tube a projecting force and a rotational movement of sufficient velocity to cause the tube to generate a cylinder of rotation on ascending to a maximum elevation, and to return substantially to its starting point along substantially the same 40 path of movement.

2. A device of the class described comprising in combination: a thin-walled light-weight tube of a height exceeding the thickness of its wall, a head for supporting the tube in position to be 45 projected into the air, a shaft to be inclined from the vertical supporting the head in fixed relation thereto, and means to impart to the shaft and head a sudden projecting force and a rotational movement of sufficient velocity for projecting 50 the tube upwardly to a maximum height along a line of flight substantially axially of the inclined shaft, and for rotating the tube for generating a cylinder of rotation substantially co-axial with the axis of the shaft during both the ascent and 55 descent of the tube, whereby the tube in descent returns substantially to its initial position upon the supporting head.

3. A device of the class described comprising in combination: a projectile ring of thin-walled 60 light-weight tubing, a head tapering gradually to a size larger than the ring interior for supporting the ring in position to be projected into the air, a shaft fixed to the head, and means for simultaneously imparting to the shaft and 65 head a sudden projecting force and a rotational movement, whereby the ring is rapidly rotated about its axis as it leaves its position upon the tapered head.

70 4. A device of the class described comprising in combination: a projectile ring having the

shape of a short transverse section of thin-walled tubing, and means for projecting said ring upwardly with an axially rotating movement along a line of flight, so as to generate a cylinder of rotation which is substantially coaxial with the line of flight, said projecting means including a shaft having a handle end and an opposite end, a finger grip element rotationally and slidably supported by the shaft intermediate the shaft ends, a spring having opposite ends fixed to the 10 handle end of the shaft and to the finger grip element, respectively, to afford yielding relative movements of said handle end and finger grip element both rotationally and longitudinally, and a ring-supporting head tapered gradually to a 15 size larger than the ring interior, fixedly mounted on the opposite end of the shaft.

5. A device of the class described comprising in combination: a projectile ring having the shape of a short transverse section of thin-walled 20 tubing, and means for projecting said ring upwardly with an axially rotating movement so as to sustain itself along a line of flight inclined from the vertical, by generating a cylinder of rotation which is substantially coaxial with the 25 line of flight, said projecting means including a shaft having a handle end and an opposite end, a finger grip element rotationally and slidably supported by the shaft intermediate the shaft ends, a spring having opposite ends fixed 30 to the handle end of the shaft and to the finger grip element, respectively, to afford yielding relative movements of said handle end and finger grip element both rotationally and longitudinally, and a ring-supporting head on the opposite end 35 of the shaft, shaped to initially support the ring substantially at right angles to the shaft and to receive the descending ring in flight.

6. A device of the class described comprising in combination: a projectable ring having the 40 shape of a short transverse section of thin walled cylindrical tubing, and means for projecting said ring upwardly with an axially rotating movement along a line of flight which is inclined relative to the vertical, so as to generate a cylinder of 45 rotation which is substantially coaxial with the line of flight during both the ascent and descent of the ring, said projecting means comprising a shaft with a ring-supporting and projecting head fixed thereon, and means for imparting to the head a sudden projectile movement and a simultaneous rotational movement of sufficient force to project the ring in substantially the manner stated.

7. A device of the class described comprising 55 in combination: a projectable ring having the shape of a short transverse section of thin walled cylindrical tubing, and means for projecting said ring upwardly with an axially rotating movement along a line of flight, so as to generate a 60 cylinder of rotation which is substantially co-axial with the line of flight, said projecting means comprising a shaft with a ring-supporting and projecting head thereon, and manually operated yielding means for imparting to the 65 head a sudden projectile movement and a simultaneous rotational movement of sufficient force to project the ring in substantially the manner stated.
